PLASTIC CONTAINER FOR LIQUIDS

Joseph L. Greenwell, 8501 SW. 129th Terrace,
Miami, Fla.

Filed Aug. 14, 1964, Ser. No. 81,295

Term of patent 14 years

(Cl. D58—17)

FIG. 1

FIG. 2

FIG. 3

FIG. 4

FIG. 5

FIG. 1 is a side elevation of a plastic container for liquids showing my new design.

FIG. 2 is a top plan view thereof.

FIG. 3 is a bottom plan view thereof.

FIG. 4 is a front elevation thereof.

FIG. 5 is a rear elevation thereof.

The side not shown is the same as that shown in FIG. 1.

I claim:

The ornamental design for a plastic container for liquids, as shown and described.
